UNITED STATES PATENT OFFICE.

GEORGE MARCELLUS BADGER AND GEORGE T. BADGER, OF QUITMAN, GEORGIA.

WHEEL.

1,008,517.

Specification of Letters Patent. Patented Nov. 14, 1911.

Application filed March 29, 1909. Serial No. 486,447.

To all whom it may concern:

Be it known that we, GEORGE MARCELLUS BADGER and GEORGE T. BADGER, both citizens of the United States, and residents of the town of Quitman, in the county of Brooks and State of Georgia, have invented certain new and useful Improvements in Wheels, of which the following is a specification.

This invention consists of a new and useful construction of spring wheels.

The several features of our invention and the various advantages resulting from their use conjointly or otherwise will be apparent from the following description and claims.

In the accompanying drawings, making a part of this specification and in which similar characters of reference indicate corresponding parts,—Figure 1 is a side view of a wheel embodying our invention,—a part 15 of the side cover of the wheel being broken away to disclose the construction of parts otherwise hidden. Fig. 2 is a cross section of the outer circular portion of the wheel, illustrating a construction where two springs 20 are employed. Fig. 3 is a perspective detail view illustrating a form of plate and sockets for the seating of two springs. Fig. 4 is a detail view in perspective of one of the hinge connections between the body of the 25 wheel and its outer or peripheral tire. Fig. 5 is a side elevation of a portion of the outer portion of the wheel, and illustrating one mode of connecting two springs to the hinge and to the wheel body rim and to the 30 tread wire. Fig. 6 is a side elevation of a portion of a wheel, similar to that shown in Fig. 5, and illustrating another mode of connecting two springs to the hinge. Fig. 7 is a side elevation of our improved hinge 35 when the hinge is made double, that is, when two of these hinges are combined as one in combination with springs connected thereto. Fig. 8 represents a cross section of a portion of the wheel shown in Fig. 1, and 40 shows one mode, the preferred one, of combining a spring with the said portion of the wheel, the section being taken in the plane of the dotted line 8, 8. Fig. 9 represents by a cross section the spring of Fig. 8 held in a 45 socket at the tread rim, as well as at the wheel body rim. Fig. 10 is a side elevation of the outer portion of the wheel illustrating, in a general way, the substitution of a rubber spring in place of the metal spring 50 shown elsewhere in the drawings.

We will now proceed to describe our in-

vention in detail. We first provide a wheel body of any suitable construction. The wheel body shown in Fig. 1, and which is a good type of a strong wheel body, consists 55 of a nave, or hub A, and a felly or circular rim B. This felly is duly connected to the hub A in any proper manner,—modes of such connection being well known. In the present illustrative instance, we have shown 60 the felly connected to the hub by the spokes A². Where this felly B is of wood and also preferably where the felly is of metal, we locate upon the periphery of this felly a metal ring B², which latter serves where 65 the felly is of wood to bind it and the spokes and the hub strongly together after the manner of a common metal tire of an ordinary road vehicle, and, in any case, where the felly is of metal or of wood, 70 serves as a convenient means for holding the several devices which we locate between this felly and the outer rim or rim tread hereinafter described. For convenience of description, we shall denominate the felly 75 (whether single or compound) adapted to receive and hold such devices as the "wheel body rim". We also provide an outer circular rim C located at a desired distance 80 from the wheel body rim. This outer circular rim C is preferably of metal and is adapted to make connections with the devices interposed between it and the wheel body rim. This rim C may constitute the outer or tread tire of the wheel, but preferably another circular rim C² is located outside of this rim C and upon it. This latter rim C² is of any suitable material, and is preferably of rope or rubber, and constitutes the outer tire. This outer rim, whether 85 single as when of rim C only, or of more rims than one, as in the combination of rims C and C², we shall denominate for convenience of description as the "rim tread". Between this wheel body rim and the rim 90 tread, we locate a series of hinges F. One leaf F³ of the hinge is pivotally connected at F⁵ to the wheel body rim, and the other leaf F⁴ of this hinge is pivotally connected at F⁶ to the rim tread. The two leaves F³ and F⁴ of the hinge are at one end pivoted 95 together, viz.: at F⁷. The pivotal connections F⁵ of these leaves are suitably respectively connected to the wheel body rim and to the rim tread. In the present illustrative 100 instance, the connections employed are each a plate F⁸, having a cylindrical portion or 105 a plate F⁹, having a cylindrical portion or 110 a plate F¹⁰, having a cylindrical portion or

eye F^8 interfitting the eyes F^9 , F^9 of the adjacent hinge leaf and connected thereto by a rod F^{10} extending through said eyes F^9 , F^8 , F^9 . Suitable bolts or screws F^{12} serve to connect one plate F^7 to the wheel body rim and the other plate F^7 to the rim tread.

The direction in which the wheel rotates when the vehicle is moving forward is indicated by the arrow W , and although the hinge will operate, if its position is reversed, yet the preferred and most effective position of the hinge is shown in Fig. 1, where, when a given hinge is at the bottom of the wheel, its pivotal end F^9 is in front of the rest of the hinge.

Special attention is called to the fact that we make each leaf of the hinge inflexible and rigid. In our improvement, it has been demonstrated that the leaf must be rigid, or it will not be of use in our improvement.

The hinge we use as a driver, so that the driving rotary motion communicated through the wheel body and the wheel body rim is in turn imparted to the hinge and through it to the rim tread. If the hinge (driving means) were flexible, then, when the vehicle is turning corners, the flexibility of the hinge would cause the rim tread to play laterally relatively to the wheel body, and the wheel body to get out of the plane in which the rim tread is. In such event, this temporary dislocation of the said parts of the wheel will be likely to wreck the machine, and will always strain the wheel. Such flexibility of the leaf or leaves of the hinge will also materially interfere with the durability of the wheel, and will limit much of the life of the wheel. Therefore, on the grounds of safety from danger, and of economy of use and of practical efficiency secured, we construct each leaf inflexible and rigid. This construction of the hinge and its arrangement between the wheel body rim and the rim tread allows free movement of the wheel body and to and from the wheel body rim, and no movement laterally of the rim tread relative to the plane of the wheel body. With a rim tread and wheel body so connected as to thus admit of the rim tread approaching the wheel body rim, and again moving from the latter, we combine an elastic means for keeping the rim tread away from the wheel body rim, for permitting the rim tread to elastically approach and to elastically move away from the wheel body rim, according as the rim tread strikes obstacles, which communicate a thrust in a vertical plane to the rim tread and to the vehicle.

Obviously the elastic means interposed between the wheel body rim and the rim tread may be varied and be of different kinds. Thus in Fig. 10, we have shown a rubber spring G interposed between the wheel body rim and the rim tread. The

bottom of this spring is held in position on the wheel body rim preferably as shown, namely: by a socket H , and also held in position on the rim tread preferably by a socket H^2 . The preferred mode of connecting each socket to its adjoining rim is by bolts or screws or rivets H^4 , extending through a plate or flange H^3 of the socket, and screwed into the adjacent rim.

In Figs. 1, 8 and 9, we have shown a spring K located similarly to the spring G , but consisting of coiled metal rod. Such a spring as K is preferable to the rubber spring, because it (the spring K) is stronger than the rubber spring G , and more inflexible laterally and more durable. Fig. 2 illustrates two of such springs K , located side by side, and Fig. 3 shows a preferred mode of supporting the sockets H^2 respectively for their reception. Such duplication of springs increases the resistive power of the elastic agency employed in the wheel. As a holding device for such a spring, the sockets H and H^2 , one at each end of the spring K , may be employed as they are in Fig. 10, in connection with the rubber spring G . But the outer socket H^2 , namely: the one attached to the rim tread, may be dispensed with. That end of the spring which is next the rim tread will be free to move advantageously slightly forward or backward on the rim tread, and if so moved will remain operative, and will not get out of working position.

The socket plate H^3 , whose socket H receives that end of a spring G or K , which is next to the wheel body rim, is suitably secured in place. In Figs. 1 and 10, we have shown this socket plate H^3 as secured in place by screw bolts H^4 , screwed into the wheel body rim. A very convenient and simple mode of securing this socket plate H^3 is shown in Fig. 8, and consists of the screw bolt having a shank M^2 and a round head M , the said bolt shank and bolt head being shown in dotted lines. The said round bolt head extends into the coil of the spring K . Thus the empty space within the spring is utilized, and the socket plate H^3 , which may be then diminished in size, be securely held in place.

The combination already specified of wheel body rim, rim tread and interposed inflexible leafed-hinge and spring, located as mentioned, constitutes an effective and operative one, and produces a wheel of great strength, durability and resiliency. But where the spring is so located, and if no springs are directly combined with the hinge, the pivotal point F^6 of the jointed leaves, whenever the wheel meets with a decided obstruction it has to mount, it will move toward a rim of the wheel and against the same. Such impingement is obviously a disadvantage. For this reason, we provide the

following construction. At the pivotal end F^e of a hinge F , we provide one of the leaves F^s or F^4 with an extension F^{13} rigid therewith, and extending out from the hinge substantially as shown. At each side of this plate (extension) F^{13} we locate a spring. One of these springs L is between the wheel body rim and said extension F^{13} , and the other spring L^2 is located between the said extension 10 and the rim tread. Both of these springs L and L^2 are preferably held in place by a connection with the said extension F^{13} . One mode of such holding consists in the sockets F^{15} , F^{16} , secured respectively to the 15 felly portion of the wheel, and to the outer rim portion of the wheel. Into each socket, the adjacent end of one of the said springs enters. Another mode of holding these springs L and L^2 in place when these springs 20 are coiled ones consists in centrally locating that terminal end of the spring which is next to the said extension, forming it in an eye L^3 and bolting it to the extension F^{13} . Both springs are preferably bolted with 25 one bolt or rivet L^4 ; see Fig. 6, where the eyes L^3 , L^4 are shown, but the rivet is properly not seen.

Among the functions which the springs perform which are interposed between the 30 rigid extension plate of the hinge and the rim tread and wheel body rim, as above described, we mention the following: There are two independent springs, one above the extension and one below the said extension 35 of the hinge, put in to hold the center of the pivot end of the hinge in as near a central location as possible while long standing. Then any shock or jar that the outer or rim tread may have, will compress one of these 40 springs absorbing the shock before reaching the axle of the wheels, resulting in prolonging the life of the machinery and engine. By having one spring on each side of this 45 extension provides for a shock absorber either in going backward or forward. These said devices perform the functions of a shock absorber whether the shock comes from the engine, which shock usually occurs in throwing from one clutch to the other in changing 50 the speed of a machine, or when the shock comes from the outer rim of the wheel in meeting obstacles on an uneven road.

Now as to applying power through the 55 hinge,—the power of the vehicle being applied through the wheel to the suspension hinge, and pulling on one leaf F^s and pushing on the other leaf F^4 , transmitting the power from the inner rim to the outer rim tire has 60 a tendency, as the whole rotates, to compress that end spring L which is next the wheel body rim, and thus throw the point of the application of power on the point of contact of the wheel rim. As the wheel rolls 65 forward, this compression of the hinges at

the lower portion of the wheel takes place, as an obstacle is struck, and this compression occurs for a distance along the wheel body rim, so that a rear part of the rim tread is raised before it reaches the obstacle. As the tread rim is thus raised, it assists in helping the vehicle over the obstacle. When power is applied to the wheel, the power is distributed through the hinge compressing the spring at the extension of 70 the hinge, transferring the point where the power is applied to the wheel rim, as for instance, at X , out along the hinge leaf F^s to the point F^e and thence to the point between the springs L and L^2 , and thus locating 75 the point where the power is applied through the springs, to a place on the wheel, in advance of the point where the rim tread is in contact with the ground and to the unevenness or obstacles to travel thereon 80 found. If the wheel is going forward, it will compress one of the springs L , L^2 , and release the other. When the wheel is going backward, it will compress the other of the springs L , L^2 , and release the other, with 85 the understanding that the machine is moving forward in the direction shown by the arrow Z , at the center line of the wheel, Fig. 1, and the wheel being rotating in the direction of the arrow W . In case the engine 90 suddenly starts up or suddenly increases its speed, it will, when the wheel is going forward, compress spring L and release spring L^2 , but when the wheel is going backward under such conditions as to the sudden 95 movement of the engine, the spring L^2 will be compressed and the spring L will be released. For this reason, while it is possible to operate a hinge F having an upper 100 rigid leaf FD^2 , formed of two outer leaves FD^4 , FD^4 , pivotally united, an inner rigid leaf FD^5 formed of two inner leaves FD^8 , FD^8 , pivotally united and pivoted substantially as described and illustrated in Fig. 7, 105 said leaves having the extension FS^{13} and the sockets FS^{14} , and we include such a form within one feature of our invention, such 110 form is obviously not nearly so advantageous as where in the hinge shown in Fig. 1, the rim tread has great freedom to alter its 115 position relatively to the wheel body rim.

Our invention is of primary importance in and for the wheels of vehicles where the wheels must sustain heavy weights, and the vehicles are driven at a high rate of speed 120 upon roads other than tramways and railroads; also where comfort of riding and absence of jar and of vertical thrust is desired for the persons riding in said vehicle; also where articles of a fragile nature, or 125 such as are easily injured by concussion or jar are to be conveyed.

By our invention, the movement of the vehicle is easy; the wheels are durable. The wheels, of course, cannot be punctured, and 130

they avoid all of the expense and delay and trouble consequent upon puncturable tires.

Our invention is comparatively economical in construction, efficient in use and of 5 great durability.

What we claim as new, and of our invention and desire to secure by Letters Patent, is:—

1. The herein described improvement in 10 wheels comprising a wheel body having a rim, a rim tread surrounding the rim and spaced apart therefrom, a three point suspension hinge having inflexible leaves pivoted together at one end, the other ends of the 15 respective leaves being pivotally attached to the inner side of the rim tread and to the outer side of the wheel body rim, a rigid extension secured at the pivotal connection of the leaves, said extension being rigid relatively to one leaf of the spring, and springs 20 located respectively between the extension and the rim tread on one side and the wheel body rim on the other.

2. The herein described improvement in 25 wheels comprising a wheel body having a rim, a rim tread surrounding the rim and

spaced apart therefrom, a three point suspension hinge having inflexible leaves pivoted together at one end, the other ends of the 30 respective leaves being pivotally attached to the inner side of the rim tread and to the outer side of the wheel body rim, a rigid extension secured at the pivotal connection of the leaves, said extension being rigid relatively to one leaf of the spring, and 35 springs located respectively between the extension and the rim tread on one side and the wheel body rim on the other, and springs bearing between the inner side of the rim tread and the outer side of the wheel body 40 rim and independent of the three point suspension hinge for giving resiliency to the wheel.

GEORGE MARCELLUS BADGER,
GEORGE T. BADGER.
